UNITED STATES PATENT OFFICE.

DAVID DILLON LONG, OF MOLLIE, NORTH CAROLINA, ASSIGNOR OF ONE-FOURTH TO JESSE JAMES TODD, OF CLARENCE, NORTH CAROLINA, AND ONE-FOURTH TO M. L. HARDIE & CO. AND ONE-FOURTH TO SAMUEL CHESTER LONG, BOTH OF MOLLIE, NORTH CAROLINA.

STOVE.

1,185,811.

Specification of Letters Patent.

Patented June 6, 1916.

Application filed October 3, 1914. Serial No. 864,848.

To all whom it may concern:

Be it known that I, DAVID DILLON LONG, a citizen of the United States, residing at Mollie, in the county of Columbus and 5 State of North Carolina, have invented a new and useful Stove, of which the following is a specification.

The present invention relates to improvements in stoves, and more particularly to 10 that character of stove adapted to be used upon farms for scalding hogs or the like, one object of the invention, being the provision of a stove of this character in which the heat from the burning fuel is caused to travel 15 erse in a substantially circular direction so that the outer rim as well as the lowermost portion of the pot or boiler is heated.

A further object of the present invention, 20 is the provision of a stove of this character which is simple, inexpensive and durable in construction, and which is readily transported from place to place.

With the foregoing and other objects in 25 view which will appear as the description proceeds, the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

In the drawings—Figure 1 is a front elevation of the complete stove showing the 35 fuel introducing door and the flue. Fig. 2 is a top plan view of the complete stove. Fig. 3 is a section taken on line 3—3 of Fig. 2.

Referring to the drawings, the numeral 1 designates the outer cylindrical member 40 of the stove, and 2 the inner cylindrical member, said members being disposed concentrically and having the space therebetween at the top sealed by the annular rim 3, so that a heat insulating material 4 may be disposed within the space. This heat insulating material is preferably earth or some other material that is readily at hand, 45 as the lower ends of the respective members 1 and 2 are adapted to rest upon the ground. It will be noted, by referring particularly to Figs. 2 and 3, that the rim 3 is located below the upper ends of the members 1 and

2, thus to form an annular gutter to receive 55 any overflow from the kettle 6.

The member 2 extends beyond the upper edge of the member 1 and is provided with the kettle receiving rim 5, so that the kettle or boiler 6 is disposed thereon as clearly 60 illustrated in Fig. 3. A draft and fuel admitting opening 7 is provided through both of the casings 1 and 2, while leading from the chamber formed by the casing 2, at a point not far distant from the opening 7, 65 is the flue 9.

Mounted within the casing 2 and disposed to cause the products of combustion to follow the direction of the arrows as illustrated in Fig. 2, is a baffle plate 8, 70 whose upper edge is curved at 8' to receive the lower portion of the boiler 6, so that the boiler 6 co-operates therewith in preventing the products of combustion to pass above the upper edge of the baffle 8 so that the 75 normal draft will flow through the door opening 7 in the direction of the arrows, as illustrated in Fig. 2 and finally out of the flue 9. By this means, the heat is distributed to the full area of the bottom of the 80 boiler and to the outer rim thereof so that the contents thereof is thoroughly heated.

What is claimed is:

1. A stove comprising inner and outer concentric members spaced apart, a connection between the upper end portions of the members, the inner member extending upwardly beyond the connection to form a seat, a kettle removably and snugly fitted within the upper portion of the inner member and bearing downwardly on said seat, said members having an air inlet and a smoke outlet in the walls thereof and close together, and a baffle plate extending between the air inlet and the smoke outlet 95 and fitting snugly against the bottom of the kettle, said baffle plate being extended past the center of the space within the inner member and constituting a supplemental support for the kettle. 100

2. A stove comprising inner and outer concentric members spaced apart, a connection between the upper end portions of the members, the inner member extending upwardly beyond the connection to form a seat, a kettle removably and snugly fitted within the upper portion of the inner member and bearing downwardly on said seat, 105

said members having an air inlet and a smoke outlet in the walls thereof and close together, and a baffle plate extending between the air inlet and the smoke outlet 5 and fitting snugly against the bottom of the kettle, said baffle plate being extended past the center of the space within the inner member and constituting a supplemental support for the kettle, there being an an-

nular gutter between the members and 10 above the connection.

In testimony that I claim the foregoing as my own, I have hereto affixed my signature in the presence of two witnesses.

DAVID DILLON LONG.
